TUNING ARRANGEMENT FOR ELECTRIC OSCILLATIONS

Werner Puhlmann and Erich Gossel, Berlin, Germany, assignors to C. Lorenz Aktiengesellschaft, Berlin-Tempelhof, Germany, a company

Application October 8, 1938, Serial No. 233,924
In Germany October 19, 1937

2 Claims. (Cl. 178—44)

In circuit arrangements for very short waves, especially those of the decimeter range, it is well known to employ an inductance connected directly to the grid and anode of an electron tube. Such arrangements are in the nature of three-point feedback connections of the kind in which the capacities of the oscillatory circuits are constituted by the inter-electrode capacities. The inductance of the circuit is a bail, for instance, having tubular members one of which is arranged to slide in the other after the manner of a trombone slide, thus providing for the adjustment of the inductance.

Tuning arrangements of this type have the disadvantage that the surfaces of contact of the said bail members allow high frequency currents to flow through the bail, whereby through variation of the transition or contact resistance losses are easy to occur in the circuit.

For the avoidance of this drawback the invention in order to provide for frequency adjustment proposes to fit such a bail-shaped inductance with a displaceable conductive body by which the electric properties of the bail circuit are influenced, this being probably due to capacitive detuning.

The invention will be understood from the following description, reference being had to the accompanying drawing, in which

Fig. 1 shows the well known circuit arrangement of devices of this kind, Fig. 2 is a partially sectioned view of a tuning arrangement as provided by the invention, Fig. 3 shows a section on line 3—3 of Fig. 2.

In the arrangement represented in Fig. 1 an oscillatory circuit 2 is joined to the grid and anode of a three-electrode tube 1. This circuit is interrupted in direct-current fashion by a condenser 3 in order to supply to the tube an adjustable anode voltage from A and an adjustable grid voltage from G. The grid voltage is supplied over a resistance 4.

As the capacity of the oscillatory circuits is substantially defined by the inter-electrode capacity, a frequency adjustment is obtained by influencing the inductance. Such influence, as stated before, is in accordance with the invention effected by varying the position of a conductive body with respect to this inductance. In the case of Figs. 2 and 3 such conductive body 6 is a solid metal body fastened to an insulating body 7. The bodies 6, 7 are carried by a set screw 8 having its thread engaged by thread

provided in a support 9 made of an insulating material. Screw 8 is rotatably secured in body 7. This is guided in the cross bar of a bail 14, being seated in an aperture 5 thereof. Bail 14 is a solid metal body of rectangular cross section.

Since in this way body 6 does not contact with the bail 14, that serves as the said inductance, any difficulties arising through such contact are avoided. The electron tube 1 may be mounted on bail 14.

By rotating the screw 8 the assembly 7, 6 can be displaced within the bail to effect the desired frequency adjustment.

With an arrangement of this kind and a wavelength of 50 centimeters, for instance, it has been possible to obtain a frequency variation amounting to +10 per cent.

What is claimed is:

1. A tuning arrangement for electric oscillations comprising an oscillatory circuit, a metallic generally U-shaped inductance having parallel sides and a cross bar provided with a non-circular aperture included in said oscillatory circuit, a non-circular insulating body fitting in said aperture to resist rotation while allowing sliding movement, a cross bar supported on said body and extending across said U-shaped inductance from one parallel side to the other but out of contact with both said sides, screw means for sliding said insulating body through said aperture parallel to said sides of said U-shaped inductance, whereby the position of said conductive body may be changed with respect to said inductance.

2. A tuning arrangement for electric oscillations comprising an oscillatory circuit, a metallic generally U-shaped inductance having parallel sides and a cross bar provided with a non-circular aperture included in said oscillatory circuit, a non-circular insulating body fitting in said aperture to resist rotation while allowing sliding movement, a cross bar supported on said body and extending across said U-shaped inductance from one parallel side to the other but out of contact with both said sides, a set screw rotatably attached to said insulating body, and an insulating support having a thread enmeshed with said screw whereby rotation of said screw imparts sliding motion to said insulating body for adjusting said conductive body along the sides of said U-shaped inductance.

WERNER PUHLMANN.
